PROCESS OF NEUTRALIZATION

Lyle Caldwell, Long Beach, Calif., assignor, by
mesne assignments, to California First National
Bank of Long Beach, Long Beach, Calif., a
national banking association, as trustee

Application October 14, 1930, Serial No. 488,573

5 Claims. (Cl. 196—41)

This invention relates to a process for neutralizing oils and a method of application therefor, in which oils which have been subjected to an acid treatment may have acidity neutralized.

5 In my copending application, which has matured into Patent No. 1,921,116, Aug. 8, 1933, I have disclosed a process of neutralization for said oils in which a mineral, such as a brucite, is very effective in the presence of moisture to form water soluble salts of the acids which are then removable by washing with water.

In the present invention I have found that many minerals may be used for neutralization of acid oils, and prefer that such neutralizing 15 minerals are added to the oils in excess of the theoretical amount calculated for neutralization.

Such minerals include raw impure materials, such as calcined magnesite (MgO), dolomite ($Ca.MgCO_3$), or calcite ($CaCO_3$), which minerals 20 are high in MgO , $Mg(OH)_2$, CaO or $Ca(OH)_2$, and are particularly serviceable on account of their high neutralizing qualities, giving values of from 6.5 to 6.9 on the pH scale.

Such minerals may form either water soluble, 25 or water insoluble, acid reaction compounds or a combination of the two when used together, and my present process is directed to the substantially complete utilization of such minerals.

This is accomplished by grinding the raw material, which may be calcined, or partly calcined, magnesite, dolomite, calcite, or other suitable minerals, or a mixture of any and all of them, to a fine powder of from upwards of 50 mesh, preferably of about 200 mesh, which sizing will cause 35 the material to be suspended in the acid oil to be neutralized for a prolonged period and give an extended contact surface.

A simple manner of effecting the neutralization of acid oils is illustrated in the accompanying 40 drawing, wherein an agitating tank 10 is supplied with acid stock in suitable quantity through a pipe 11.

The acidity of the oil having been determined, a quantity of the ground neutralizing material 45 is then introduced into tank 10, through hopper 12, and such quantity is preferably 25% in excess of the quantity necessary theoretically to combine with all the acid in the oil.

Should the neutralizing material, or the acid 50 stock, not contain sufficient water or moisture to provide for the necessary chemical reactions, the same may be introduced in the proper amount through pipe 13.

A pump 14 then picks up the mixture from tank 55 10 and forces the same through pipes 15 and 16,

and valve 17 to be rapidly circulated through tank 10, valve 18 being closed.

Such circulation insures a thorough contacting of the acid oil and neutralizing material and may be aided by a mechanical agitator 19, to the end 60 that after a predetermined period of agitation a neutralization is effected by the formation of a quantity of either water soluble or water insoluble compounds.

After such period valve 17 may be closed and 65 valve 18 opened, whereupon the mixture of treated oil and reaction products is forced into a second tank 20, into which a bleaching clay or filter aid, or mixture thereof, may be introduced through hopper 21, whereupon a pump 22 rapidly 70 circulates the mixture through a pipe 23 and valve 24 to tank 20, the valve 25 being closed.

After a predetermined period of agitation, 75 which may be aided by a mechanical agitator 27, valve 24 is closed and valve 25 opened to permit 80 the mixture to be forced through a filter 26, wherein the acid reaction compounds, bleaching clay, and the like, are separated from the neutralized and clarified oil which passes to storage through pipe 28 and water trap 29.

The use of tank 20 is desirable but unnecessary 85 in the process, the addition of bleaching clay or the like merely adding to the efficiency of the oil treatment as a whole, and tank 20 may at times be replaced by either a step of sedimentation or thickening, or both, prior to or excluding separation in filter or centrifuge 26.

Alternatively, decolorizing material may be used concurrently with the neutralizing material in tank 10, in which case tank 20 may be unnecessary.

A satisfactory cheap neutralizing material for use in tank 10 is dolomite, which gives pH values approaching 7.0 and which yields a mixture of magnesium and calcium sulphates which is removed in the filter 26, but I do not limit myself to the use of this material but include as well the use of any solid neutralizing agent which is chemically reactive with the acid constituents of an oil to form compounds of a separable nature 100 in the presence of sufficient water to supply at least the water of hydration in such compounds.

It is, of course, obvious that there may be sufficient water in the original acid stock used to supply the water necessary, in which case no further water need be put into tank 10, but a certain quantity is necessary to form such compounds as are easily separated in filter 26 from the oil which is then a clarified and neutral oil of stable properties ready for any further final treatment 110

prior to use after the removal of any excess water caught in trap 29.

I claim as my invention:

- 5 1. A process of neutralization which comprises contacting sulphuric acid treated oil with powdered dolomite in the presence of water to form water insoluble reaction compounds, then separating said compounds from the oil.
- 10 2. A process of neutralization which comprises contacting sulphuric acid treated oil with powdered dolomite in the presence of water to form water insoluble reaction compounds, then separating said compounds from the oil; said dolomite being present in an amount not less than 15 10% in excess of that theoretically required to neutralize the acid.
- 15 3. A process of neutralization which comprises: contacting sulphuric acid treated oil with calcined powdered dolomite in the presence of

20

water to form water insoluble reaction compounds, then separating the oil and said compounds.

4. A process of neutralization which comprises: contacting sulphuric acid treated oil with calcined powdered dolomite of not less than 200 mesh in the presence of water to form water insoluble reaction compounds, then separating the oil and said compounds.

5. A process of neutralization which comprises: contacting sulphuric acid treated oil with calcined powdered dolomite in the presence of water to form water insoluble reaction compounds, then separating the oil and said compounds; said dolomite being present in an amount in excess of that theoretically necessary to neutralize residual acid in the oil.
